UNITED STATES PATENT OFFICE.

ROY E. LEONARD, OF LOS ANGELES, CALIFORNIA, ASSIGNOR OF ONE-HALF TO DAVID G. LORRAINE, OF DALLAS, TEXAS.

LONG-STROKE PUMP-OPERATING MECHANISM.

Application filed December 19, 1927. Serial No. 241,097.

This invention is an operating mechanism for deep well pumps, and has for its object to obtain a relatively long stroke with minimum expenditure of power, and to provide 5 for relatively slow movement of the operating mechanism when reversing its direction of reciprocation at the ends of the stroke in order to insure complete opening and closing movement of the valvular means which 10 is controlled by the operating mechanism.

It is a further object of the invention to insure reciprocation of the operating mechanism without deviation from the straight line of its longitudinal axis, and to apply 15 power to the operating mechanism at diametrically opposite points so as to maintain a balanced driving connection.

It is a still further object of the invention to provide an extremely simple and durable 20 construction which is positive in its operation, and which provides for automatic lubrication of its moving parts, and is readily mounted on a derrick floor and operatively connected to the usual polished rod of the 25 pump mechanism of a well.

Further objects of the invention will be readily understood from the following description of the accompanying drawings, in 30 which:

Fig. 1 is a front elevation of the invention with the front plate of its housing partly broken away.

Fig. 2 is a similar side view of the invention.

Fig. 3 is a transverse section on the line 35 3—3 of Fig. 1.

Fig. 4 is a diagrammatic illustration of the reversal of the stroke of the operating mechanism.

The invention is adapted for mounting on 40 the derrick floor A of a well so as to straddle the casing head and tubing from which the usual polished rod B projects, and the operating mechanism engages the polished rod so 45 as to provide a long stroke reciprocation for operating the pump in usual manner.

The housing for the operating mechanism 50 comprises a curved dome 1 extended to form depending front and rear walls 2, which at their lower ends provide a forked construction 3 forming transversely spaced vertical pockets having inner side walls 4. The upper ends of the side walls 4 are connected by a base 5, and the lower ends of the pockets 55 are closed by curved extensions 6 of the

forked ends of the walls 2, with these extensions providing a supporting base 7 having corner lugs 8 for bolting the housing to the derrick floor. The sides of the housing are 60 closed by the plates 9.

Bearings 10 project from the side plates 9 medially of their width and height, and shafts 11 are journaled in these bearings and are adapted for rotation in opposite directions with pinions 12 fixed on their inner ends 65 and projecting into the housing at opposite sides thereof. A cross head 13 is pivoted at its respective ends to vertical rack bars 14 which are thus adapted for dependent vertical reciprocation in the housing adjacent 70 the respective side plates 9, and the rack bars are provided with continuous racks 15 extending along their front and rear vertical edges and around their curved ends, with the racks of the respective bars adapted to mesh 75 with the respective pinions 12, at either side thereof.

With the parts in the position shown in Fig. 3, the rack bars are adjacent the front and rear walls respectively of the housing so 80 that the rack bars mesh with opposite sides of their respective oppositely rotating pinions and are thereby both reciprocated downwardly, and at the end of the stroke of the rack bars the curved ends of the racks remain in 85 mesh with their pinions and the rack bars are thereby moved around their pinions and thus oppositely shifted as permitted by the turning of cross head 13 so that the racks are then adjacent the rear and front walls respectively 90 of the housing as shown in dotted lines in Fig. 3, with the other vertical edge of each rack in mesh with the other side of its pinion for reversing the stroke of the rack bars by 95 the continuous turning of the pinions in the same respectively opposite direction. At the upper end of their stroke the rack bars are similarly oppositely shifted so as to resume the position shown in full lines in Fig. 3 so 100 that the other vertical edge of each rack bar again meshes with the other side of its pinion to provide the downward stroke of the rack bars.

The rack bars are guided in their vertical reciprocation and movement around their 105 pinions by a suitable guiding means adapted to continuously maintain the rack bars in mesh with their pinions, and for this purpose guide tracks 18 may be mounted in the housing laterally beyond each of the rack bars 110

14, with each of said tracks extending along the vertical front and rear walls 2 and around the dome 1 and curved extensions 6, so that cooperating guide rollers 19 journaled on the 5 rack bars 14 at their respective ends will engage the tracks and thus maintain the rack bars in meshing engagement with their pinions.

It will be noted that at the lower end of 10 the stroke of the rack bars the guide rollers 19 at the lower ends of the bars will remain in engagement with the tracks 18, but the guide rollers at the upper ends of the rack bars will disengage the tracks during movement of the 15 rack bars around their pinions as shown in Fig. 4, and that similarly at the upper end of the stroke of the rack bars, while the upper rollers 19 will remain in engagement with tracks 18, the lower rollers 19 will disengage 20 the tracks as shown in dotted lines in Fig. 4. Means are preferably provided for guiding these ends of the rack bars at which the rollers 19 do not remain in engagement with tracks 18 during shifting of the racks, and for this 25 purpose guide rollers 21 on the rack bars may engage guide tracks 22 so as to maintain the racks in meshing engagement with their pinions during shifting movement of the rack bars around their pinions as shown in Fig. 4.

30 The guide rollers 21 project from the rack bars adjacent their respective ends but in such position as to clear the tracks 18 as shown in Figs. 2 and 4, and the tracks 22 are mounted on the side plates 9 above and below the pinions 12, and are so curved that the rollers 21 by engaging these tracks will maintain the racks 15 in mesh with their pinions. The 35 tracks 22 are of restricted length and so positioned that the rollers 19 will clear the same, and the rollers 21 are so positioned as to afford 40 the earliest possible engagement with the tracks 22 as the ends of the rack bars move around their pinions. For this purpose the rollers 21 at the respective ends of each rack bar are in close proximity to the respective vertical toothed edges of the rack bar as 45 shown in Fig. 2, and as a consequence the roller 21 at the lower end of the rack bar will clear the track 22 which is below pinion 12, while the roller 21 at the upper end of the 50 rack will engage this track during completion of the downward stroke of the mechanism as shown in Fig. 4, and the roller 21 at the upper end of the rack will clear, and the roller 21 at the lower end of the rack will engage, the track 22 which is above the pinion 12, during 55 completion of the upward stroke of the mechanism as shown in dotted lines in Fig. 4.

Reciprocation of the rack bars as thus described is adapted to reciprocate the polished rod B which extends vertically through the housing when the latter straddles the casting head. The polished rod extends through the cross head 13 which is free to turn on the 65 rod, and the polished rod is fixed to the cross

head for reciprocation therewith by means of usual clamps 30.

The pivotal connections between the rack bars and the cross head preferably comprise slotted lugs 31 projecting from the rack bars 70 and adapted to receive bearing heads 32 at the ends of the cross head between the same. Pivot pins 33 extend through the bearing heads and into the slots of lugs 31, thereby permitting swinging of the cross head with 75 relation to the rack bars as the latter are shifted from one side to the other of their pinions, and the slots which receive the pivot pins provide for the necessary play at the pivotal connections in order to prevent binding of the parts, and for a similar purpose the rack bars are preferably recessed in alignment with the bearing heads 32 as shown at 35, in order to clear the outer ends of the bearing heads when the cross head is turned. 80

The upper end of the polished rod B preferably projects above the housing with a clamp 40 fixed thereon and adapted to compress a relatively heavy coiled spring 41 as the rack bars approach the lower end of their stroke, and as soon as the rack bars pass beyond lower dead center, the compressed spring by its abutment against clamp 40 initiates the upward stroke of the mechanism 90 and thereby moves the rack bars to a position where the pinions 12 engage the vertical portions of the racks 15 for providing a positive driving connection. During the upward stroke the clamp 40 moves clear of the expanded spring 41, and the weight of the mechanism and the string of sucker rods depending therefrom moves the rack bars beyond upper dead center so as to again positively engage the vertical portions of racks 15 by the operating pinions. 95

100 The pockets formed between the inner side walls 4 and side plates 9 are closed except at their upper ends and are so positioned as to receive the lower ends of the rack bars at the completion of the downward stroke; and a suitable lubricant is contained in these 110 pockets for the purpose of lubricating the racks 15 and thereby transmitting the lubricant to the cooperating teeth of the pinions 12 for providing an automatically lubricated 115 operating connection.

The driving connection whereby the pinions 12 are oppositely rotated is shown as comprising facing beveled gears 50 fixed on shafts 51 and oppositely rotated by a co-operating beveled pinion 52 which is fixed on a drive shaft 53. Sprockets 54 may be mounted on the shafts 51, and suitable sprocket chains 55 may cooperate therewith and engage sprockets 56 on the pinion shafts 120 11 for oppositely rotating the pinions. 125

By the construction as thus described, I have provided extremely practical means for obtaining a relatively long stroke for a deep well pump, the rack and pinion operating con- 130

nection insuring reciprocation of the polished rod in a straight line and provided for the long stroke reciprocation with a minimum expenditure of energy. The construction also 5 provides for long stroke reciprocation with relatively slow reversal of the direction of the stroke as a result of the rack bars moving around their drive pinions, and as a consequence the reciprocation is such as to take 10 up slack in the string of sucker rods and permit complete opening and closing of the valve of the pump at each reversal of the stroke.

I claim:

1. A reciprocating driving connection comprising oppositely rotating pinions, rack bars having curved ends with continuous racks extending along their side edges and around their curved ends and adapted to mesh with either side of the respective pinions for reciprocating the rack bars, and a cross head pivotally connected to the rack bars so as to permit swinging of the cross head and shifting of the rack bars from one side to the other of their respective pinions as the curved portions of the racks move around their cooperating pinions at the respective ends of the stroke of the rack bars.

2. A reciprocating driving connection comprising oppositely rotating pinions, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating pinions at the respective ends of the stroke of the rack bars, and means for guiding the rack bars during reciprocation thereof so as to maintain the racks in meshing engagement with their pinions.

45 3. A reciprocating driving connection comprising oppositely rotating pinions, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating pinions at the respective ends of the stroke of the rack bars, and means for guiding the rack bars during movement of the racks around their cooperating pinions so as to maintain the racks in meshing engagement with their pinions.

4. A reciprocating driving connection comprising housing forming pockets adapted to 65 contain a lubricant, oppositely rotating pin-

ions mounted in the housing, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating pinions at the respective ends of the stroke of the rack bars, and the said reciprocating and shiftable rack bars extending into the said pockets during said movement of the rack bars.

5. A reciprocating driving connection comprising oppositely rotating pinions, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating pinions at the respective ends of the stroke of the rack bars, and a spring adapted for compression by movement of the rack bars toward the end of their stroke and adapted to move the rack bars beyond dead center as the curved ends of the racks move around their cooperating pinions.

6. A long stroke operating mechanism for a deep well pump comprising a housing adapted for mounting on a derrick floor so as to straddle the casing head of the well with the polished rod of the pump projecting upwardly through said housing, oppositely rotating pinions mounted in the housing, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of racks move around their cooperating pinions at the respective ends of the stroke of the rack bars, the cross head providing for projection of the said polished rod therethrough at the axis of its swing, and means for fixing the polished rod to the cross head for reciprocation therewith.

7. A reciprocating driving connection comprising oppositely rotating pinions, rack bars having curved ends with continuous racks extending along their side edges and around their curved ends and adapted to mesh with either side of the respective pinions for reciprocating the rack bars, a cross head piv-

totally connected to the rack bars so as to permit swinging of the cross head and shifting of the rack bars from one side to the other of their respective pinions as the curved portions of the racks move around their cooperating pinions at the respective ends of the stroke of the rack bars, and means for guiding the rack bars during reciprocation thereof so as to maintain the racks in meshing engagement with their pinions, the said guiding means comprising cooperating tracks and anti-frictional contact means.

8. A reciprocating driving connection comprising oppositely rotating pinions, rack bars having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating pinions at the respective ends of the stroke of the rack bars, tracks following the path of travel of the side edges and curved ends of the rack bars during reciprocation thereof, and anti-frictional contact means at

the ends of the rack bars cooperating with 30 said tracks for maintaining the racks in meshing engagement with their pinions during reciprocation of the rack bars.

9. A reciprocating driving connection comprising oppositely rotating pinions, rack bars 35 having curved ends with continuous racks extending along their side edges and around their curved ends and adapted to mesh with either side of the respective pinions for reciprocating the rack bars, a cross head pivotally connected to the rack bars so as to permit swinging of the cross head and shifting of the rack bars from one side to the other of their respective pinions as the curved portions of the racks move around their cooperating 40 pinions at the respective ends of the stroke of the rack bars, tracks following the path of travel of the ends of the rack bars around the pinions, and anti-frictional contact means at the ends of the rack bars 45 cooperating with said tracks for maintaining the racks in meshing engagement with their pinions during movement of the racks around their cooperating pinions.

In testimony whereof he has affixed his 55 signature to this specification.

ROY E. LEONARD.
